UNITED STATES PATENT OFFICE.

WILL J. CAMERON, OF CHICAGO, ILLINOIS.

VARIABLE-RESISTANCE UNIT.

Application filed May 9, 1921. Serial No. 467,973.

To all whom it may concern:

Be it known that I, WILL J. CAMERON, a subject of the King of Great Britain, and citizen of the Dominion of Canada, residing at Chicago, Cook County, Illinois, United States of America, have invented certain new and useful Improvements in a Variable-Resistance Unit, of which the following is a full, clear, and exact description.

10 My present invention relates to a variable resistance unit, and has for its object the provision of a simple and convenient device whereby different desired amounts of resistance may be conveniently placed in a 15 circuit thereby altering the conductivity of the circuit and controlling the action of such apparatus as it is desired to interpose in the circuit. This device may be conveniently used, for instance, for controlling 20 the action of an electric heating device, also for dimming an ordinary commercial incandescent bulb, or for reducing an ordinary service current so that it will be suitable for apparatus requiring less than the 25 ordinary amount of current such as miniature incandescent bulbs.

I prefer to attain my objects in the manner and by means of the instrumentalities illustrated in the accompanying drawing in 30 which,—

Figure 1 is a longitudinal side view of a resistance unit involving my invention having a portion of the casing broken away for clearness.

35 Figure 2 is a central longitudinal section of the structure shown in Figure 1, an incandescent bulb being shown in the socket thereof, and,

Figure 3 is a transverse section taken on 40 line 3—3 of Figure 1.

Figure 4 is a diagram of the circuit connection.

Similar reference characters refer to similar parts throughout the several views.

45 The core of my device consists of a centrally bored or centrally apertured cylinder 5 of suitable insulating material, such as porcelain, insulating composition, or built-up or composition mica, the surface of 50 which has a suitable coil or helix 6 imbedded therein of suitable resistance wire, and of which there are several kinds upon the market. The imbedding of the helix is secured by proper applications of suitable 55 insulating material after the helix is wound

in place upon the original core. At the lower end and then skipping to the center and extending from about the central portion of this coil or helix toward the upper end is a series of spaced contact elements 7, 60 which extend from different convolutions of the imbedded coil or helix to the surface of the cylinder 5, through the insulating coating.

A preferably flat rod of copper 8 extends longitudinally of the cylinder 5 and is 65 spaced therefrom and assembled therewith by means of disk-shaped centrally bored ears 9, produced laterally from each end of the rod 8 to lie over and adjacent the opposite ends of the cylinder 5. The cylinder 5 is surrounded for the greater portion of its extent with a split reticulated cylindrical jacket 10, the upper edge thereof extends into an annular groove 11 in the lower edge or face of an insulating cap block 12, 70 while the lower end of the jacket 10 extends into a like annular groove 13 in an insulating socket block 14 which is provided with a socket 15 in its opposite face. Both the cap block 12 and the socket block 14 are 75 centrally bored at 12^a and 14^a so as to register with the central bore 5^a in the cylinder 5, and also a central bore 16^a in an insulating plug piece 16, the outer longitudinal surface whereof is provided with a preferably threaded shell 17 of conducting material.

80 A headed central bolt 18 passes through the central bore 16^a in the plug piece, the bore 12^a in the cap block, the bore 5^a in the cylinder, and the bore 14^a in the socket block, besides the central bores in the disks or ears 9, from which however it is insulated, and with a nut 19 serves to unite and bind the above-mentioned parts together, and also to form a central contact for the plug piece 16 and the socket 15. To secure a firmer holding of the ears 9 an intermediate nut 20 is screwed onto the bolt 18, so as to come immediately above the 90 upper ear 9, from which it is insulated by means of the insulating washer 21.

95 The cap block 12 is eccentrically but longitudinally bored at 22 for the passage of a conductor 23 which connects the threaded shell 17 on the plug piece 16 with the ear of the bar 8.

100 The socket block 14 is also longitudinally and eccentrically bored at 24 for the passage of a conductor 25, from the lowermost con- 105

tact blocks 7 to a conducting threaded shell 26 carried in and adjacent the sides of the socket 15.

An insulating runner block 27 is provided 5 with opposite longitudinal channels 28 into which extend the longitudinal edges of the split reticulated cylindrical jacket 10 and secured upon the bottom of the runner block 27 by means of a screw 29 is an electric conductor or bridging piece 30, one end of which remains continually in contact with the rod or bar 8 in all positions, and the other end of which may be brought by the movement of the block 27 successively into contact with 10 any of the contact blocks 7.

While a small amount of current will always pass through the helix or coil 6 when the circuit is closed by the insertion of a suitably connected terminal plug 31 in the 20 socket 15 the greater portion of the current will pass from the threaded shell 17 through conductor 23 to the rod or bar 8, and from thence through the bridge piece 30 to the particular contact block 7 with which the 25 opposite end of the bridge piece may be in contact. The current will then flow from the particular contact block 7 with which the bridge piece is in connection to the lowermost point of the coil or helix 6 through the 30 conductor 25, threaded shell 26, plug 31 or other apparatus, back through the bolt 18 to the central contact of the plug piece 16.

It will be seen that the entire resistance 35 element may be cut out of the circuit without detaching the unit by bringing the bridge piece 30 into contact with the lowermost of the contact elements 7.

What I claim as new is:—

1. A variable resistance unit comprising a 40 hollow insulating core, a helix of resistance metal wound thereabout, a series of spaced contact elements secured respectively to different convolutions of said helix, a layer of insulating material covering said helix and 45 all but the outer faces of said contact elements, a conductor disposed longitudinally of and spaced from said core and helix, a longitudinally slotted casing surrounding said core and conductor, an insulating slide 50 mounted in the slot of said casing, and a conductor bridge carried by said slide and extending from said conductor to alignment with said series of contact elements.

2. A variable resistance unit comprising a 55 hollow insulating core, a helix of resistance metal wound thereabout, a series of spaced contact elements secured respectively to different convolutions of said helix, a layer of insulating material covering said helix and

all but the outer faces of said contact elements, a conductor disposed longitudinally of and spaced from said core and helix, a longitudinally slotted casing surrounding said core and conductor, an insulating slide 60 mounted in the slot of said casing, a conductor bridge carried by said slide and extending from said conductor to alignment with said series of contact elements, a centrally bored plug and socket, and a single bolt extending through the bores of said elements and constituting one element of a circuit between and the central terminals of said plug and socket.

3. A variable resistance unit comprising a core of insulating material, a length of wire 75 of resistance material coiled around said core, a series of spaced contact elements secured to spaced convolutions of said wire, a layer of insulating material covering said core and coils and exposing the outer faces 80 of said contact elements, a straight conductor extending parallel with said core, a movable bridge one portion thereof constantly engages said straight conductor and the opposite portion is adapted to successively contact said contact elements, and means for slidably mounting said bridge.

4. A variable resistance unit comprising an insulating core, a resistance coil around said core, a plurality of spaced contacts 90 engaging respective portions of said coil, a conductor extending longitudinally of said core and spaced from said coil, a movable bridge engaging said conductor and successively engaging said contacts, a conductor 95 extending longitudinally through said core and beyond the ends thereof, plug and socket shells spaced from the ends of said central conductor, and circuit conductors respectively connecting one of said shells to said 100 coil and the other of said shells to said spaced conductor.

5. A variable resistance unit comprising a core of insulating material, a conductor disposed longitudinally of and spaced from 105 said core, a resistance coil around said core, a bridge movable longitudinally upon said conductor and successively engaging convolutions of said coil, and plug and socket members disposed at opposite ends of said 110 core, said plug and socket members respectively connected with said coil and said conductor and having independent electrical connection between the same.

Signed at Chicago, county of Cook and 115 State of Illinois, this 3d day of May 1921.

WILL J. CAMERON.
